CLAIM

The ornamental design for a storage container, as shown and described.

DESCRIPTION

FIG. 1 is a perspective view of a storage container showing my new design;

FIG. 2 is an exploded perspective view thereof;

FIG. 3 is a top plan view thereof;

FIG. 4 is a bottom plan view thereof;

FIG. 5 is a right side elevation thereof;

FIG. 6 is a left side elevation thereof;

FIG. 7 is a front elevation thereof; the rear elevation being a mirror image thereof;

FIG. 8 is an exploded perspective view of a second embodiment of FIG. 1; and,

FIG. 9 is a front elevation of FIG. 8; the rear elevation being a mirror image thereof.

The right and left side elevations of FIG. 8 are similar to as shown in FIGS. 5 and 6.

FIG. 1

FIG. 2

FIG. 3

FIG. 4

FIG. 5

FIG. 6

FIG. 7

FIG. 8

FIG. 9
